UNITED STATES PATENT OFFICE.

WALTER P. MURPHY, OF CHICAGO, ILLINOIS.

SHEET-METAL END STRUCTURE FOR RAILWAY-CARS.

1,186,493.

Specification of Letters Patent.

Patented June 6, 1916.

Original application filed November 25, 1912, Serial No. 733,369. Divided and this application filed January 13, 1915. Serial No. 1,979.

To all whom it may concern:

Be it known that I, WALTER P. MURPHY, a citizen of the United States, residing at Chicago, in the county of Cook and State of Illinois, have invented certain new and useful Improvements in Sheet-Metal End Structures for Railway-Cars, of which the following is a specification.

My invention relates to a sheet metal end for railway cars, particularly box cars, and consists in certain novel structures and combinations whereby a car end is provided which will be light in weight, and very strong and rigid so as to be capable of withstanding shocks and pressures, for example, the inertia thrusts of shifting cargoes, and so as to act as a reinforcement for the car superstructure as a whole, and which may be manufactured and installed more economically and conveniently than the sheet metal ends heretofore employed in the construction or repair of railway cars.

Having in view particularly the hard usage to which the ends of freight box cars are subject due to shifting cargoes and like causes, cars of this sort have been equipped, either in their original construction or in the repair of broken ends, with end structures consisting of one or more sheet metal elements formed with horizontal ribs or pressed corrugations which carry the stresses exerted thereon as beams to the corner posts of the car.

The primary object of this invention is to provide a car end structure, suitable for use either in the construction of new cars or for repair purposes, consisting of a plurality of metal end sheets extending from substantially the roof of the car to the floor, suitably joined together and to the corner posts of the car along their vertical edges and provided with vertically arranged parallel corrugations extending substantially from the top to the bottom of the structure so as, in effect, to form upright load carrying members which help to support the roof and which serve to rigidify and strengthen the end wall of the car and thereby the entire superstructure thereof; the invention providing further more rigidifying members at the top and bottom of the end sheets calculated to take the stresses from the vertical corrugations and transmit them to the side frame members of the car.

The invention has for further objects such

other new and improved constructions, arrangements and devices relating to sheet metal car ends as will be hereinafter described and claimed.

The invention is illustrated in the accompanying drawings in which—

Figure 1 is an end elevation of a box or body of a freight box car provided with a sheet metal end wall structure embodying my invention. Fig. 2 is a vertical sectional view taken on line 2—2 of Fig. 1. Fig. 3 is a sectional plan on line 3—3 of Fig. 1. Fig. 4 is a view, in perspective, of the upper attaching and rigidifying member, and Fig. 5 is a similar view of the bottom attaching member.

Like characters of reference designate like parts in the several figures of the drawings.

The car end is shown for purposes of illustration as applied to a wooden box car of standard construction. The wooden end plate of the car framing is designated 10, the end sill 11 and the corner posts 12.

13 indicates the roof, 14 the end fascia plate and 15 the flooring of the car.

The end structure in the preferred form shown is composed of a corrugated panel consisting of two sheet metal elements 16, an upper rigidifying and attaching member or metal end plate element 17 (Fig. 4) and a lower angular rigidifying and strengthening member 18 (Fig. 5). The end sheets 16, 16 are formed with vertical corrugations 19 which extend across the sheets from top to bottom, that is, from the upper to the lower edges thereof. The sheets are formed on their outer lateral edges with angular flanges 20 which are secured to the corner posts 12 by any suitable means, for example, the bolts 21. The meeting edges of the sheets 16 are preferably provided with angularly disposed flanges 22 fastened together by rivets 23.

The top member or metal end plate 17 is secured to the wooden end plate 10 by bolts 24, or other suitable attaching devices and has flanges 17^b (Fig. 4) overlapping and secured to the side wall of the car. The lower edge of the top member overlaps the upper edge of the panel 16, 16 and has a corrugated or undulatory configuration corresponding with the corrugated configuration of the panel. The panel and top member are secured together preferably by rivets indicated at 25. The bottom member 18 is in the form of an angle bar having a flat

flange 26, secured to the top of the end sill 11 by bolts 27, and an upstanding flange 28 which is corrugated or given an undulatory configuration to fit the corrugations of the 5 panel 16, 16. Preferably the upstanding flange 28 is arranged on the inside of the panel the latter being secured thereto by rivets 29. In order to make the car grain proof the horizontal flange 26 of the bottom 10 member extends preferably under the flooring 15.

In the construction described a car end is provided having corrugations extending, in effect, from the roof to the floor of the car 15 so as to form load bearing elements capable of carrying some of the weight of the roof. Moreover, these corrugations because of their vertical arrangement materially strengthen and stiffen the end as against the 20 tendency of the car to weave, that is, to become distorted on diagonal lines. The construction, in each case, is waterproof.

A sheet metal car end constructed in the preferred manner shown and described, 25 besides having the structural advantages noted can be very cheaply manufactured.

By forming the sheets with corrugations extending from one edge to the other the corrugating operation may be performed in 30 an ordinary corrugating machine by a continuous process and in some cases without heating the metal. There is no tendency to thin down any part of the sheet. It will be seen that the top and bottom members 17, 35 18, however, provide, in the first place, a rigid reinforcement extending in a direction transverse to the corrugations so that deflection by the pressing out of the corrugations which would otherwise take place 40 when the end was subjected to a heavy cargo thrust, is effectually prevented. Each corrugation acts as a post or upright beam transmitting stresses, such as the thrusts of the lading, to the upper and lower edges 45 of the sheet. In the construction described, the metal end plate takes the stresses thus transmitted to the upper edges of the sheets and carries them to the side frame members of the car. In effect, the corrugations extend 50 over upon the metal end plate, although this is not essential to the function in question. With a vertically corrugated end it is important that the upper edges of the sheet or sheets be thus provided with means for 55 taking the stresses of the corrugations and transmitting them to the side walls of the car, since the roof of a box car is ordinarily the weakest part of the structure and is little calculated to take the heavy stresses 60 resulting from shifting cargoes. It is also important that the lower edge of a vertically corrugated end sheet be provided with a transversely extending rigidifying member capable of taking the stresses from the 65 corrugations and transmitting them to the car

frame, because, while the end sill is more capable of taking the stresses on the corrugation than the roof of the car, ordinarily the impact of the load on the end of the car will be nearer the floor than the roof, so that 70 the stresses at the bottom of the end structure are greater than those at the top. As to both upper and lower edges, the need for reinforcement is much greater than where the corrugations run horizontally, because 75 in that case each corrugation constitutes a beam transmitting the stresses against it directly to the corner posts and side walls of the car. In the end wall construction described, each corrugation preferably merges 80 into the next, so that the structure has a sinuous configuration in cross-section. As a result, end stresses against the corrugation are transmitted in part to the adjacent corrugations with the result that undue deflection 85 at any given point or along any given line which might result in rupture of the metal is avoided. Moreover, the top and bottom members provide a convenient means for attaching the corrugated sheets to the 90 upper and lower frame members of the car. The structure at these places is perfectly waterproof. The angular configuration of the bottom piece 18 makes the end structure tight at the flooring of the car. This is 95 important as box cars are used very extensively for carrying grain.

This application is a division of my co-pending application Serial No. 733,369, filed November 25, 1912. The subject matters 100 common to this application, the parent application, and my co-pending divisional application, Serial No. 93661, filed April 26, 1916, are claimed generically in said last mentioned two cases and not in this application, which, by amendment, has been restricted to one of the embodiments of the invention originally disclosed.

I claim:

1. In a railway box car the combination 110 with the under frame and side walls of the car, of an end plate comprising a metal element extending across the upper part of the car and secured to the side walls thereof, metal end sheets secured together and to 115 the side walls of the car along their vertical edges and formed with vertical corrugations, means for securing the upper edges of said end sheets to the said metal end plate element and means for securing the lower 120 edges of the sheets to the under frame of the car.

2. In a railway box car the combination 125 with the under frame and side walls of the car, of an end plate comprising a metal element extending across the upper part of the car and secured to the side walls thereof, metal end sheets secured together and to the 130 side walls of the car along their vertical edges and formed with vertical corruga-

tions, the lower edge of said metal end plate element being overlapped, fitted to and secured to the upper edge of the end sheets providing a water shedding connection.

- 5 3. In a railway box car the combination with the under frame and side walls of the car, of an end plate comprising a metal element extending across the upper part of the car and secured to the side walls thereof, 10 metal end sheets secured together and to the side walls of the car along their vertical edges and formed with vertical corrugations, means for securing the upper edges of said end sheets to the metal end plate element and means providing a flange angularly disposed with respect to the end sheets for securing the lower edges of said end sheets to the under frame.
- 4 In a railway box car the combination 20 with the under frame and side walls of the car, of an end plate comprising a metal element extending across the upper part of the car and secured to the side walls thereof, metal end sheets secured together and to the 25 side walls of the car along their vertical edges and formed with vertical corrugations, means for securing the upper edges of said end sheets to said metal end plate element and an angle bar secured to the lower 30 edges of said sheets and to the under frame of the car.

5. In a railway box car the combination with the side walls, end sill and flooring of a railway box car, of an end plate comprising a metal element extending across the upper part of the car and secured to the side walls thereof, metal end sheets secured together and to the side walls of the car along their vertical edges and formed with vertical corrugations, means for securing the upper edges of said end sheets to said metal end plate element, and an angle bar secured to the lower edges of said sheets and extending and intervening between the flooring of 45 the car and the end sill and attached to the latter.

6. In a railway box car the combination with the corner posts, end sill and end plate of the car, the latter comprising a metal element extending across the car from side to side and provided at its extremities with angularly disposed flanges overlapping and secured to the sides of the car; of end sheets having their adjacent vertical edges overlapped and secured together, and provided with flanges on their outer vertical edges overlapping and secured to said corner posts, and means for securing the lower edges of said sheets to the end sill of the 50 car; the lower edge of said metal end plate element being offset so as to overlap and fit the upper edges of said end sheets and their flanges providing a water shedding connection.

65 7. In a railway box car the combination

with the corner posts, end sill and end plate of the car, the latter comprising a metal element extending across the car from side to side and attached to the side walls thereof, of end sheets secured together and to the 70 corner posts along their vertical edges, with their upper edges secured to said metal end plate element, and means for securing the lower edges of said sheets to the car frame providing a horizontally disposed flange 75 which overlies and is secured to the end sill of the car.

8. In a railway box car the combination with the corner posts, end sill and end plate of the car, the latter comprising a metal element extending across the car from side to side and attached to the side walls thereof, of end sheets secured together and to the corner posts along their vertical edges, with their upper edges secured to said metal end plate 80 element, means for securing the lower edges of said sheets to the car frame providing a horizontally disposed flange which overlies and is secured to the end sill of the car, said 85 end sheets being formed with vertical corrugations which extend substantially from the top to the bottom of the end structure of the car so as to transmit stresses exerted against the same to the metal end plate element and to the flange attached to the end 90 sill.

9. In a railway box car the combination with the under frame and side walls of the car, of an end plate comprising a metal element conformed to the slope of the roof of 100 the car extending across the upper part of the car and secured to the side walls thereof, metal end sheets secured together and to the side walls of the car along their vertical edges and formed with vertical corrugations, 105 means for securing the upper edges of said end sheets to the said metal end plate element and means for securing the lower edges of the sheets to the under frame of the car.

10. In a railway box car the combination with the frame and side walls of the car, of an end plate comprising a metal element extending across the upper part of a car and secured to the side walls thereof, metal end sheets secured together and to the side walls of the car along their vertical edges and formed with vertical corrugations which extend to the upper edges of the sheets, the lower edge of said metal end plate element being conformed to fit the corrugated upper edges of the end sheets and being secured thereto, and means for attaching the lower edges of said sheets to the under frame of the car.

11. In a railway box car, the combination with the under frame and side walls of a car, of metal end sheets secured together and to the side walls of the car along their vertical edges and formed with vertical corrugations 125 extending to the edges of the sheets, and a 130

metal element extending across the car from side to side and secured to the end frame thereof provided with a flange, to fit the corrugated edges of said sheets, to which said sheets are secured.

12. In a railway box car the combination with the under frame and side walls of the car, of an end plate comprising a metal element extending across the upper part of the 10 car and secured to the side walls thereof, metal end sheets secured together and to the side walls of the car along their vertical edges and formed with vertical corrugations extending to the upper and lower edges of 15 the sheets, the lower edge of said metal end plate element being conformed to the corrugated upper edges of the sheets and said sheets secured thereto; and a metal member extending across the car from side to side 20 and secured to the under frame, provided with a flange, conformed to the corrugated

lower edges of the sheets, to which said sheets are secured.

13. In a railway box car, the combination with the under frame and side walls of the 25 car of an end plate comprising a metal element extending across the upper part of the car and secured to the side walls thereof, metal end sheets secured together and to the side walls of the car along their vertical 30 edges and formed with vertical corrugations which merge one into the other so that the structure has a sinuous configuration in cross-section, said sheets being secured at their upper edges to said metal end plate element, and a transverse metal element at the lower edges of said sheet secured thereto and to the under frame of the car.
